UNITED STATES PATENT OFFICE.

GEORGE C. KINNEY, OF BISHOP, CALIFORNIA.

FISH SCREEN.

Application filed June 9, 1927. Serial No. 197,562.

My invention relates to a self-cleaning fish screen device particularly designed for use in an artificial waterway and including a current wheel disposed in the stream of the 5 waterway.

An object of the invention is to provide a novel mounting for the current wheel whereby the wheel, while normally disposed to have the blades thereof sweep in fixed paths with 10 respect to the bed of the waterway, may be so displaced by and upon a lodgment of débris thereunder as to allow the escape of the débris.

Another object of the invention is to provide a generally improved structure for a device of the character described which will require a minimum of attention.

The invention possesses other objects and features of advantage, some of which, with 20 the foregoing, will be set forth in the following description of the preferred form of the invention which is illustrated in the drawings accompanying and forming part of the specification. It is to be understood, however, that variations in the showing made by the said drawings and description may be adopted within the scope of the invention as 25 set forth in the claims.

Referring to said drawings,

30 Figure 1 is a plan view of the device.

Figure 2 is a side view of the device.

Figures 3 and 4 are end sectional views taken respectively on the lines 3—3 and 4—4 in Figure 2.

35 As herewith particularly disclosed, the device of my invention is incorporated with and carried by a flume section 6 providing a water channel 7 of rectangular cross-section and arranged to be inserted in a waterway.

40 In the present embodiment of the invention, the section 6 is formed of concrete and is open at the top, with the channel 7 defined between opposed side walls 8 which extend upwardly from a bottom wall 9. Mounted in 45 the channel adjacent the bottom thereof to extend transversely thereacross is a roller 11, such roller being here shown mounted on stub-shafts 12 extending axially from the roller and journalled in the walls 8. Pivot-

50 ally mounted at the outer sides of the walls 8 for rotation about the axis of rotation of the roller 11, is a pair of strut members 13, these members being of such length that when disposed to slope upwardly from their pivoted

55 ends at an angle of about 45 degrees, they will protrude above the top edges 14 of the walls 8.

A roller 16 is carried by and between the upper ends of the struts 13 on stub shafts 17 extending therefrom and journalled in the strut ends.

60 It will now be noted that the rollers 11 and 16 are arranged to cooperatively carry an endless and flexible belt or band 18 formed of a suitable screening, and that the struts 13 are preferably of adjustable length whereby 65 the rollers may be adjusted to so engage the band that rotation of either roller will effect a rotation of the band about the rollers. The pivotal mounting of the struts 13 permits 70 an angular adjustment thereof and the struts are preferably so positioned as to dispose the plane portions of the band to slope upwardly 75 of the lower roller 11 in a down-stream direction and at an angle of substantially 45 degrees, adjustably positionable stops 20 being provided on the outer sides of walls 8 for supportably engaging the struts. The band 18 is preferably of a width to have its side edges so disposed with respect to the walls 8 as to prevent the passage thereby of objects 80 too large to pass through the interstices of the band, and the lower roller 11 is so disposed with respect to the bottom of the channel as to prevent the movement of such objects under the roller. Preferably, teeth 19 85 are provided on the rollers for engagement with the band 18 for insuring the rotation and proper positioning thereof.

It will now be clear that an appropriate 90 rotation of the screen carrying rollers will cause the upstream surface of the screen to be moved obliquely upwardly out of the stream whereby any débris lodging against the screen will be carried away to prevent clogging of the screen, and a water wheel 21 95 for effecting such movement of the rollers is accordingly provided. The water wheel 21 may be of any suitable structure, and as here shown, is formed with blades 22 mounted on and connecting the arms of spiders 23 fixed 100 on a shaft 24, which shaft is carried in bearing blocks 26 mounted on the opposite walls 8. Journalled on a stub-shaft 27 extending outwardly from one of the blocks 26 in parallel spaced relation from the shaft 24 is 105 a gear 28, such gear being arranged to maintain a meshed engagement with a gear 29 fixed on shaft 24. As here shown, the gear 28 carries a chain sprocket 31, while the appropriate stub shaft 17 of roller 16 is provided 110 with a chain sprocket 32, the sprockets 31 and 32 being disposed in coplanar relation

for operative connection by means of a chain belt 33. In this manner, a belted and geared connection between the wheel and belt rollers is provided in such a manner as to produce the desired movement of the belt as the wheel revolves in the stream. It will, of course, be obvious that while the wheel is here shown mounted in down-stream relation to the screen, it might, if desired, be placed in upstream relation thereto without affecting the operative relations involved.

Preferably the wheel is disposed to have its various blades normally sweep close to the bottom wall 9 whereby the immersion of the blades will always be a maximum. But under such conditions, débris carried by the stream is liable to become wedged between a blade and the bottom 9 before the blade reaches its lowest point of travel whereby, if means are not provided for releasing such débris, the rotation of the wheel may be stopped and the device thus rendered inoperative. Accordingly, the bearing blocks 26 are not fixed with relation to the walls 8, but are slidably mounted for displacement from the bottom ends of upwardly directed guideways 34 provided in members 36 secured to the walls as by bolts 37—as here shown, the guideways are provided in the members 36 by forming them of pairs of fixedly related opposed channels 38. In this manner it will now be clear that in the event of débris collecting between a blade and the bottom, the wedging of such débris beneath a blade will exert a lifting force through the wheel spokes carrying it whereby the upward displacement of the wheel will be effected and the débris and blade will be allowed to move forwardly until the former is clear of the latter, after which the wheel will resume its normal position.

To insure a displacement of the wheel in the manner specified, a part of the weight of the wheel and bearing block structure is preferably arranged to be counterbalanced by means of counter-weights 39, such weights being mounted on the free ends of cables 41 fixed to the bearing blocks 26 and carried over pulleys 42 mounted on the members 36. In this manner, the débris releasing displacement of the wheel may occur without necessitating the building up of an unduly large wedging effect by the débris. To permit the requisite upward displacement of the wheel, the sprockets 31 and 32 are preferably so spaced that a certain amount of slack is provided in chain 33, it being noted that the necessary adjustment is provided by means of the adjustable positioning of the stops 20 against which the struts 13 of the screen mounting rest.

It will now be particularly noted that the

use of the water wheel mounting of my invention eliminates the necessity for removing the débris from the stream thereat, so that the usual provision of a conveyor belt for catching the débris as it falls from the moving screen after the latter passes over roller 16 and conveying the débris to one side of the screen is thus rendered unnecessary. In this manner the elimination of the necessity for actually removing the débris from the stream produces a simplified mechanism which involves a minimum of parts, may be left unattended for long periods, and at the same time permits the normally fixed disposition of the wheel in the stream for a maximum immersion thereof.

I claim:

1. In a device of the character described, the combination of a flume, a fish screen of the endless belt type mounted in said flume, a water wheel supported on a rotatable shaft and disposed in the channel of said flume, bearing blocks for said shaft supported by said flume and displaceable upwardly from their normal position, and means operatively connecting said shaft to said screen.

2. In fish screen mechanism of the character described, an operating water wheel therefor carried on a rotatable shaft, a bearing block for said shaft, and a fixed support for said bearing block arranged to normally support said block during operation of the mechanism and to permit a displacement of the block therefrom in a predetermined direction.

3. In a device of the character described, the combination of a flume, a fish screen of the endless belt type mounted in said flume, a water wheel disposed in said flume and operatively connected to said screen, bearing members for said wheel normally and displaceably supported on said flume, and means carried by said flume providing an upwardly directed guideway for said bearing members.

4. In fish screen mechanism of the character described, an operating water wheel therefor, a bearing block for said wheel, a fixed member providing an upwardly directed guideway for said bearing block at the bottom of which said bearing block is arranged to be normally disposed in supported engagement with the flume, and a counter-weight arranged to maintain a lifting force on said bearing block in the direction of said guideway whereby the necessary force for lifting said wheel and block will be less than the weight force at said block.

In testimony whereof, I have hereunto set my hand at Bishop, California, this 31 day of May, 1927.

GEORGE C. KINNEY.
